UNITED STATES PATENT OFFICE.

EDMUND J. FEENY, OF MUNCIE, INDIANA.

AUTOMOBILE RADIATOR.

1,424,455.

Specification of Letters Patent. Patented Aug. 1, 1922.

Application filed September 24, 1917. Serial No. 192,846.

To all whom it may concern:

Be it known that I, EDMUND J. FEENY, a citizen of the United States, residing at Muncie, in the county of Delaware and State 5 of Indiana, have invented a new and useful Automobile Radiator, of which the following is a specification.

It is the object of my invention to increase the heat-dissipating action of the radiators 10 of internal combustion engines, particularly of automobile and tractor engines, and to use in this heat dissipation the heat-absorbing qualities resulting from evaporation of water in contact with the heat-radiating surfaces of the radiator.

In carrying out my invention, I associate with any ordinary radiator means for supplying water to the exposed heat-radiating surfaces thereof, so that the passage of the 20 air over such heat-radiating surfaces will evaporate the water thus supplied to increase the cooling effect of the radiator. Preferably, I supply the water to the heat-radiating surfaces of the radiator by wicks 55 which lie against such surfaces so that they do not interfere with the passage of the air through the air passages of the radiator, forming these wicks so that they may readily be associated with the ordinary radiator.

The accompanying drawings illustrate my invention. Fig. 1 is a front view of an automobile radiator equipped with my invention; Fig. 2 is a vertical central section through such radiator, taken longitudinally 35 of the vehicle, showing the general arrangement of the system; Fig. 3 is a fragmentary horizontal section through the radiator, showing how the wicks are associated with the radiator; and Fig. 4 is a horizontal section through the neck of one of the water-distributing funnels.

The radiator 10 is of any ordinary or suitable construction, having a receiving header 11 at the top to which water from the water 45 jacket of the associated engine is supplied through the usual connection 12, and a discharge header 13 at the bottom from which water is supplied through the usual connection 14 to such water jacket, either by a 50 natural circulation of the system or by a circulating pump. The headers 11 and 13 are connected by vertical water pipes 15, which in the form of radiator shown are ordinary metal tubes, these tubes 15 being

arranged in a transverse series of rows, with 55 the individual rows extending longitudinally of the automobile, so that air passages 16 are provided between the rows to permit the passage of air through the radiator in the usual manner. In the radiator shown, 60 the heat-radiating surfaces furnished by the outside of the tubes 15 are augmented by horizontal heat-radiating plates 17 through which the tubes 15 project and with which they are in close contact, so that the heat 65 radiation to the air passing through the passages 16 is not only from the surfaces of the tubes 15 but also from the surfaces of the plates 17. All this is an ordinary radiator construction.

In order to increase the heat-dissipating effect by producing evaporation of water, I provide a number of zigzag wicks 20, the spacings between alternate strips of which correspond to the spacings between adjacent 70 rows of the water pipes 15, as is clear from Fig. 3. These zigzag wicks are thrust through the radiator so that they lie in the air passages 16 and closely against the adjacent horizontal plates 17 and against the 75 rows of water pipes 15. In order to facilitate thrusting these zigzag wicks through the radiator, they are preferably provided with metallic core wires 21, for stiffening them. The wicks 20 do not fill the air 80 passages 16, and the bends 22 joining adjacent strips of each zigzag wick are located completely outside of the radiator, either forward of the front face thereof or behind the 85 rear face thereof, so that they do not obstruct the entrances to and exits from the air passages 16. The zigzag wicks 20 lie between the horizontal plates 17, and are thrust into alternate spaces between such plates 17 from the front and rear of the 90 radiator respectively. The series of vertical wicks 23, at the front of the radiator and 24 at the rear of the radiator, are provided, being located respectively in the planes of the rows of water pipes 15, the vertical wicks 95 23 at the front of the radiator being embraced by the bends 22 at the front of those zigzag strips 20 which are thrust into the radiator from the front, and the vertical wicks 24 at the rear of the radiator being 100 embraced by the bends 22 at the rear of those zigzag strips 20 which are thrust into the radiator from the rear. The vertical wicks 105

23 and 24 are brought together in one or more groups so that they may be supplied with water, this being accomplished in the arrangement shown by passing the rear vertical wicks 24 forward through some of the air passages 16 to the front of the radiator above the level of the topmost zigzag wick 20, and then extending both the front and rear vertical wicks 24 upward through flattened, inverted, water-distributing funnels 25, in the neck 26 of each of which are closely grouped half of the entire number of vertical wicks 23 and 24. The necks 26 of these funnels are open at the top, so as to 15 receive the discharge from faucets 27, which are connected by pipes 28 to a supplemental water supply tank 29 having a suitable filling opening 30. This tank 29 is conveniently located directly back of the upper or receiving header 11 of the radiator, and may extend backward over the associated engine for the entire length of the latter.

In operation, the tank 29 being filled with water, the faucets 27 are adjusted so that 25 they drip water into the necks 26 of the funnels 25 to saturate the vertical wicks 23 and 24 therein. The vertical wicks 23 and 24 conduct this water downward both in front of and behind the radiator 10, by capillary attraction, and also by capillary attraction 30 this water is taken up from the vertical wicks 23 and 24 by the horizontally extending zigzag wicks 20, the bends 22 of which are in close contact with the vertical wicks. 35 The horizontal zigzag wicks carry the water they receive, horizontally, into the air passages 16, and into contact with the plates 17 and water pipes 15. When in operation the cooling water circulates from the water 40 jacket of the associated engine through the connection 12 to the upper or receiving header 11 of the radiator, down through the pipes 15 to the lower or discharge header 13, and back through the connection 14 to the water jacket, and the cooling air travels 45 through the radiator by way of the air passages 16, such cooling air not only absorbs heat direct from the pipes 15 and the plates 17 and thereby produces a cooling of the 50 water in the radiator, but also produces an evaporation from the wicks 22 and from the surfaces of the plates 17 and pipes 15 of the water which is supplied thereto from the tank 29 by the vertical wicks 23 and 24 and 55 the zigzag wicks, and this evaporation produces further cooling, according to well understood principles. This combined cooling, by radiation and evaporation from the heat-radiating surfaces, greatly increases the 60 efficiency of the radiator. If a radiator of given size produces under definite conditions a certain temperature of water, 11, the addition thereto of the water-supplying arrangement of the present invention so that evaporation occurs on the heat-radiating sur-

faces will produce under the same operating conditions a lowering by many degrees of the temperature of the water.

I claim as my invention:

1. In combination with an internal combustion engine having a water jacket, a cooling radiator for said engine, said radiator having water passages, connections between said water jacket and said water passages to provide a circulating system wherein such water passages carry the cooling water of the engine, said radiator also having air passages which have metallic heat-radiating surfaces receiving heat from the water passages, and means for supplying water to the heat-radiating surfaces of said air passages so as to add the cooling effect due to evaporation to the cooling effect due to radiation. 70

2. In combination with an internal combustion engine having a water jacket, a cooling radiator for said engine, said radiator having water passages, connections between said water jacket and said water passages to provide a circulating system wherein such water passages carry the cooling water of the engine, said radiator also having air passages which have metallic heat-radiating surfaces receiving heat from the water passages, means for carrying water into said air passages so as to wet the heat-radiating surfaces thereof, and means for supplying water to said water-carrying means. 85

3. A cooling radiator for internal combustion engines, said radiator having water passages which carry the cooling water of the engine and air passages which have metallic heat-radiating surfaces receiving heat from the water passages, in combination with wicks located in the air passages of said radiator but smaller than such air passages so as to leave room for the passage of air, and means for supplying water to said wicks. 100

4. A cooling radiator for internal combustion engines, said radiator having vertical water passages and horizontal air passages, in combination with horizontally extending zigzag wicks located in said horizontal air passages but filling less than the entire space of such air passages so as to permit the passage of air, vertical wicks in contact with the horizontal zigzag wicks, and means for wetting said vertical wicks. 105

5. A cooling radiator for internal combustion engines, said radiator having vertical water passages and horizontal air passages, in combination with horizontally extending wicks located in said horizontal air passages but filling less than the entire space of such air passages so as to permit the passage of air, vertical wicks in contact with the horizontal wicks, and means for wetting said vertical wicks. 115

6. A cooling radiator for internal combustion engines, said radiator having vertical water passages and horizontal air passages, 120

in combination with horizontally extending zigzag wicks located in said horizontal air passages but filling less than the entire space of such air passages so as to permit the passage of air, vertical wicks in contact with the horizontal zigzag wicks, inverted funnels in which the vertical wicks are collected, a water tank, and valved connections for supplying water from said tank to the collected wicks in said funnels.

7. A cooling radiator for internal combustion engines, said radiator having vertical water passages and horizontal air passages, in combination with zigzag wicks projecting into said air passageways, the bends connecting adjacent strips of said zigzag wicks being located outside of said passageways so that they permit the entrance and exit of air to and from the air passageways, and means for supplying water to said wicks.

8. A cooling radiator for internal combustion engines, said radiator having vertical water passages and horizontal air passages, in combination with zigzag wicks projecting into said air passageways, the bends connect-

ing adjacent strips of said zigzag wicks being located outside of said passageways so that they permit the entrance and exit of air to and from the air passageways, said zigzag strips being inserted into the radiator alternately from opposite sides thereof, and means for supplying water to said wicks.

9. In combination with an internal combustion engine having a water jacket, a cooling radiator for said engine, said radiator having water passages, connections between said water jacket and said water passages whereby said water passages carry the cooling water of the engine, said radiator also having air passages which have metallic heat-radiating surfaces receiving heat from the water passages, and wicks exposed to the air which travels through said air passages and carrying water which receives heat from said cooling water.

In witness whereof, I have hereunto set my hand at Muncie, Indiana, this fifth day of September, A. D. one thousand nine hundred and seventeen.

EDMUND J. FEENY.
